HEEL CONSTRUCTION FOR SHOES

George Anson, Island Park, N. Y.

Original application May 19, 1943, Serial No. 487,637. Divided and this application January 5, 1944, Serial No. 517,084

2 Claims. (Cl. 36—36)

This invention relates to heels for shoes, being divisional subject matter of my copending application Serial No. 487,637 and filed May 19, 1943.

The primary object of this invention is the provision of a heel construction which will be extremely easy and economical to repair when worn and which will not require a person to be skilled in shoe repairing in order to make the repair thereto.

Another object of this invention is the provision of a heel construction including upper and lower sections, the upper section being fixed to the shoe upper and the lower section which receives the wear, being detachably secured to the upper section by an improved securing means which will prevent accidental separation of the sections and will permit a person to easily and quickly remove the lower section when worn and replace in lieu thereof a similar new section, consequently permitting the heel construction to be reconditioned at a nominal cost.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawing, in which

Figure 1 is a side elevation illustrating a fragmentary portion of a shoe equipped with a heel constructed in accordance with my invention.

Figure 2 is a fragmentary vertical sectional view showing the heel construction and its connection with the shoe upper.

Figure 3 is a fragmentary face view with the outer section of the heel construction removed and showing one of the plates attached to the upper section of the heel construction and which forms part of the connecting means between the sections of the heel construction.

Figure 4 is a plan view showing the lower section of the heel construction and the plate therefor and which forms a part of the improved fastening means between the sections of the heel construction.

Figure 5 is a sectional view taken on the line 5—5 of Figure 4.

Referring in detail to the drawing, the numeral 5 indicates a fragmentary portion of a shoe and 6 the heel construction which forms the subject matter of the present invention. The heel construction primarily consists of upper and lower sections 7 and 8. The section 8 forms the tread

for the heel construction and receives the wear, consequently if not kept in proper shape or allowed to become worn brings about distortion of the shoe as well as being uncomfortable to the wearer. Therefore, it is of the greatest importance that the section 8 be easily detachable from the section 7 when worn so that another section 8 may be quickly adapted to the section 7 to restore the shoe for further comfortable wear.

10 The upper section 7 has formed therein a channel 9 extending through opposite edges thereof. The upper section 7 is secured to the shoe upper 5 by fasteners 10 which fasteners also secure on the upper section 7 a plate 11 shaped in accordance with one face of the upper section 7 and substantially covering the channel 9. A notch 12 is provided in the plate 11 at one edge thereof and aligns with the channel. The plate 11 has an opening 13 which aligns with the channel 9.

15 20 The improved fastening means between the sections 7 and 8 of the heel besides including the plate 11, also includes a plate 14 which has formed thereon tines 15 embedded in the section 8. When the section 8 is assembled on the section 7 the plate 14 abuts the plate 11 and has formed thereon rearwardly extending hook shaped members 16 and 17. The hook shaped member 16 enters the notch 12 and engages with the plate 11 within the channel 9 while the hook shaped member 17 passes through the opening 13 and engages with the plate 11 within the channel 9. The hook shaped member 17 has a slot 18 opening through the free end thereof to receive one of the fasteners 10. In applying the section 8 onto the section 7, the section 8 is slid in a rearward direction bringing the hook shaped members 16 and 17 in engagement with the plate 11. The plates 11 and 14 have aligned openings and the section 8 has an opening 19 to align with said openings when the section 8 is properly applied to the section 7 so that a threaded fastener 20 may pass through the aligned openings and thread into a member 21 suitably secured within the channel 9. The head of the fastener 20 is countersunk in the section 8.

25 30 35 40 45 50 55 The fastener 20 when threaded into the member 21 after extending through the aligned openings in the plates 11 and 14 and the section 8 prevents sliding movement of the section 8 relative to the section 7, consequently preventing the sections 7 and 8 from becoming accidentally detached. However, it is only necessary for a person to use a screw driver or similar tool to remove the fastener 20 whence the section 8 may be slid forwardly of the section 7 to disengage the mem-

bers 16 and 17 from the plate 11, thus the section 8 may be easily withdrawn from the section 7 and substituted by another in order to recondition the heel construction.

While I have shown and described the preferred embodiment of my invention, it will be understood that minor changes in construction, combination and arrangement of parts may be made without departing from the spirit and scope of the invention as claimed.

Having thus described my invention, what I claim is:

1. In a heel construction for shoes, upper and lower sections, said upper section having a groove, metallic plates arranged between said sections, means for securing the upper section to the shoe sole and including a fastener extending through the groove, tines formed on one of said plates and embedded in the lower heel section, tongues formed on the latter-named plate in spaced parallel relation thereto and extending longitudinally of the heel, one of said tongues having a notch adapted to receive said fastener, said other plate having a slot to receive one of the tongues and

the other tongue engaging an edge of the latter-named plate and both of said tongues being engaged behind the last-named plate, within the groove.

5 2. In a heel construction for shoes, upper and lower sections, said upper section having a groove, metallic plates arranged between said sections, means for securing the upper section to the shoe sole and including a fastener extending through the groove, tines formed on one of said plates and embedded in the lower heel section, tongues formed on the latter-named plate in spaced parallel relation thereto and extending longitudinally of the heel, one of said tongues having a notch adapted to receive said fastener, said other plate having a slot to receive one of the tongues and the other tongue engaging an edge of the latter-named plate and both of said tongues being engaged behind the last-named plate, within the groove, and a removable fastener including a nut embedded in said groove and extending through the plates with its head countersunk in the lower section.

GEORGE ANSON.
